(57) **CLAIM**

The ornamental design for a license plate cover and frame, as shown and described.

DESCRIPTION

FIG. 1 is a front perspective view of an ornamental design for a license plate cover and frame;

FIG. 2 is a rear perspective view of the ornamental design for the license plate cover and frame, from a first angle;

FIG. 3 is a rear perspective view of the ornamental design for the license plate cover and frame, from a second angle;

FIG. 4 is a front view of the ornamental design for the license plate cover and frame;

FIG. 5 is a rear view of the ornamental design for the license plate cover and frame;

FIG. 6 is a left side view of the ornamental design for the license plate cover and frame;

FIG. 7 is a right side view of the ornamental design for the license plate cover and frame;

FIG. 8 is a top view of the ornamental design for the license plate cover and frame;

FIG. 9 is a bottom view of the ornamental design for the license plate cover and frame; and,

FIG. 10 is a cross-sectional view of the ornamental design for the license plate cover and frame, taken along cross-sectional line 10-10 of FIG. 4.

The features shown in broken lines depict environmental structure only and form no part of the claimed design.

1 Claim, 8 Drawing Sheets
